POWER-TRANSMISSION MECHANISM.

1,126,101.

Specification of Letters Patent. Patented Jan. 26, 1915.

Application filed December 26, 1912. Serial No. 738,526.

To all whom it may concern:

Be it known that we, MELVIN L. SEVERY and MIKARL SCUTERUD, both of Arlington Heights, in the county of Middlesex and 5 State of Massachusetts, have invented certain new and useful Improvements in Power-Transmission Mechanism, of which the following is a specification.

This invention relates to an improvement 10 in power transmission mechanisms.

The object of the invention is to provide a variable speed device comprising a driving member, a driven member, and an interposed fluid, the latter being impeded or 15 throttled in its flow through the device to vary the speed of the driven member.

In the accompanying drawing Figure 1 is a central, vertical longitudinal section of an 20 illustrative embodiment of the invention, and Fig. 2 is a section taken on the line 2—2 in Fig. 1.

As illustrated in the drawing, the device 25 comprises a cylindrical chamber or drum 10 having substantially flat end walls 12 and 14, the latter of which is connected to a driven shaft 16. The cylindrical wall of the drum is provided with a filling hole 18 closed by a screw 18, and a vent to be opened during filling but which is normally closed 30 by a screw 20. The end wall 12 is provided with a stuffing box 22 through which a crank-shaft 24 passes, said shaft having its right hand end slidably mounted in a cylindrical cavity 26 formed in the inner end of 35 the driven shaft 16. The driving shaft 24 is longitudinally stationary, while the driven shaft 16 is slidable over the same longitudinally. This end of the crank-shaft is provided with a channel 28 and vent 29 40 which communicate with the cavity 26 to prevent the trapping of any fluid in said cavity. The crank-shaft 24 is provided with a crank-pin 30 to which a plurality of piston rods 32, are connected. Although three piston rods are shown, it will be understood 45 that any number may be employed.

The piston rods 32 are connected to pistons 34, slidable in cylinders or holes 36 formed in a coned disk 37. Plates 38, 39 50 screwed to the disk 37 in which cylinders are formed engage a channel formed in the shaft 24 to prevent longitudinal movement of the cylinder member or disk 37 along said shaft, said disk being slidable on three pins

40 which project from the inner face of the 55 end wall 12 through holes 41 in said disk. The ends of the cylinders are open, and their outer end surfaces are in the surface of a cone forming the inner conical surface of a clutch. The outer member of the clutch is 60 a conical cup-shaped member 42 adapted to fit over and close the ends of the cylinders. The clutch member 42 is provided with holes 44 in its end wall 46 which provide a free circulation of the fluid 48 through the 65 device. The clutch member 42 is slidably keyed to the driving or crank-shaft 24 by a key 50 slideable in a key-way 51 in said shaft, and said member is rotatably fastened to the end wall 14 of the drum by a plate 52, which 70 engages an annular shoulder 54 formed on said member.

A plurality of expandable and collapsible 75 members 60 are mounted on the end wall 14. These may be in the form of accordion-like 80 metallic chambers each having a rod 62 which passes through said end wall and is provided with a head 64 on its outer end. When the drum 10 is to be filled with fluid 85 the members 60 are collapsed by drawing out the rods 62, and they are held in this position by spring detents 66 which engage the heads 64. After the drum is filled completely with the fluid, which may be oil, glycerin, or any other suitable fluid, and 90 sealed, the detents 66 are disengaged from the heads 64, and the accordion-like chambers 60 expand under their own resiliency to take up the room of any fluid that may pass the stuffing-box. Thus the working space 95 within the drum is kept full of fluid and the admission of air into the same is prevented.

When the oil, or other fluid is allowed to pass freely into and out of the cylinders 95 there is no motion of the driven end, but when the conical clutch-member 42, which also serves as a valve to more or less close the outer ends of the cylinders, moves toward the left by the action of the shipper, 100 then the flow of fluid from the pistons is impeded and they react upon the crank and tend to tie the crank-shaft and piston member together, and when said clutch-member 105 closes the cylinders entirely the clutch-member which is splined to the driving-shaft takes the full load, while at the same time its complete impedance to the flow of the

liquid causes the complete locking of crank and cylinder member together of itself.

This device is suitable for boats and the like where a variable speed is desired, it being merely necessary to move the shipper until the desired speed is attained.

What we claim is:—

1. The combination of two axially aligned and independently rotatable shafts; a cone clutch member connected with one of said shafts to rotate therewith and provided with a plurality of cylinder spaces having their ends open to the conical friction surface of said clutch; pistons in said cylinders; crank connections between said pistons and the second of said shafts; a complementary cone clutch member mounted to turn with said second shaft and shiftable axially with reference to the first clutch member, first to 20 throttle the ends of said cylinder openings and then to enter into frictional driving engagement; a liquid retaining casing surrounding said clutch members; and a liquid contained in said casing and adapted to be circulated by the reciprocation of said pistons.

2. The combination of a shaft; a tight casing rotatably mounted on said shaft and axially shiftable with reference thereto; a cone clutch member mounted in said casing to rotate therewith and provided with cylinder spaces having their ends open to the cone surface of said clutch; pistons in said cylinders; crank connections between said 35 pistons and said shaft; a second cone clutch member splined on said shaft and shiftable axially thereon by the axial shifting of said casing to exert a variable throttling action on said open-ended cylinders and in its limiting position to enter into frictional engagement with the first named cone clutch member; and a liquid confined in said casing

and adapted to be circulated by the reciprocation of said pistons.

3. The combination of a shaft having a crank portion; a tight casing rotatably mounted on said shaft and axially shiftable with reference thereto; a cone clutch member mounted on said shaft, held thereon against axial shifting, and in driving engagement with said casing to cause the two to rotate together, said cone clutch member having cylinders formed therein having open ends terminating on the conical friction surface of said clutch member; pistons in said cylinders; driving connections between said pistons and the crank portion of said shaft; a second and coaxial clutch member splined on said shaft and engaging said casing to be shifted axially therewith, first to throttle said cylinder openings and then to enter into frictional engagement with the first named cone clutch member; and a liquid contained in said casing and adapted to be circulated by the reciprocation of said pistons.

4. The combination with two independently rotatable members, one provided with a plurality of pump cylinders having pistons, and the other provided with driving connections to said pistons; of an axially shiftable cone clutch member splined on one of said rotary members and adapted when axially shifted, first to throttle the flow caused by the reciprocation of said pistons, and then to establish a frictional driving engagement between said rotary members.

In testimony whereof we have affixed our signatures, in presence of two witnesses.

MELVIN L. SEVERY.
MIKARL SCUTERUD.
